UNITED STATES PATENT OFFICE

SIMON P. WEISENSTEIN, OF SHALER TOWNSHIP, ALLEGHENY COUNTY, PENNSYLVANIA

DESIGN FOR A BARBECUE ROASTER

Application filed July 15, 1929. Serial No. 32,055. Term of patent 14 years.

To all whom it may concern:

Be it known that I, SIMON P. WEISENSTEIN, a citizen of the United States of America, and residing in the township of Shaler, county of Allegheny, and State of Pennsylvania, have invented a new, original, and ornamental Design for Barbecue Roaster, of which the following is a specification, reference being had to the accompanying drawing, forming part thereof.

In the drawings Fig. 1 is a front elevation of a barbecue roaster showing my design, and Fig. 2 is an end view of the same.

I claim:

The ornamental design for a barbecue roaster as shown.

SIMON P. WEISENSTEIN.
